UNITED STATES PATENT OFFICE.

ACHILL BIPPART, OF SOUTH ORANGE, NEW JERSEY.

BAR PIN.

Application filed November 4, 1922. Serial No. 599,144.

To all whom it may concern:

Be it known that I, ACHILL BIPPART, a citizen of the United States, residing at South Orange, county of Essex, and State of New Jersey, have invented certain new and useful Improvements in Bar Pins, fully described and represented in the following specification and the accompanying drawings, forming a part of the same.

10 This invention relates to means for securing a bar-pin upon the fabric of a dress in such manner as to hold the pin flat against the fabric, to prevent it from turning or rolling outwardly upon the pin-tongue, and thereby tip outwardly upon the dress, and present an unnatural and unsightly view of the pin.

15 The invention is especially applicable to bar-pins of considerable length in which the pin-tongue, although connected to the bar at both ends, is liable to bend or yield backwardly from the bar, and thus permit the pin to roll in the manner described.

20 My invention provides a means of gripping the bar-pin at the middle of its length firmly to the fabric; the body of the pin being provided near the middle of its length with a seat upon which the tongue can press the fabric firmly.

25 Such pressure is effected by curving the tongue convexly toward the body of the pin, so that its middle portion is pressed firmly upon the pin when the point of the pin is sprung inward to engage the retaining hook.

30 Such gripping of the fabric has a wholly different effect from merely thrusting the pin longitudinally through the fabric, as the pin-tongue in such case serves merely as a pivot upon which the bar-pin can readily turn or roll into an unnatural and undesirable position, which exposes the edge of the pin instead of the front.

35 The invention is especially applicable to bar-pins having a flange along the edge forming a trough-like body, and the middle seat in such cases is formed as a bridge or block between the side-flanges, upon which bridge the middle of the pin grips the material as in a vise.

40 With a pin-tongue several inches in length, the tongue is capable of yielding or bending laterally between its two ends, but when the bridge is provided, as described 45 herein, and the pin curved to press firmly upon it, the stiffness of the pin is increased

and is rendered approximately equal to that of a pin one-half its length.

50 The invention will be understood by reference to the annexed drawing, in which Fig. 1 shows the inner side of a bar-pin having my improvement, and the pin-tongue turned outward; Fig. 2 is an edge view of the bar-pin with the tongue closed; Fig. 3 is an edge view of the pin with the tongue 55 opened; and Fig. 4 is a cross section of the bar-pin on line 4-4 in Fig. 1, showing the space between the side-flanges.

55 In bar-pins heretofore made, it has been common to project the pivot-bearing and 70 the hook a material distance from the body of the bar-pin; but the purpose of the present invention is to hold the pin close to the fabric of the dress; and the pivot-bearing and hook in my construction are therefore 75 projected in a lesser degree from the body of the pin.

60 In my invention the tongue is mounted close to the body or bar, and draws the pin close to the fabric and grips it so as to 80 prevent the pin from tipping or rolling over.

65 The provision of the middle seat, the convex curving of the pin, and the limited projection of the pivot-bearing and hook all 85 contribute to the drawing of the pin close to the dress, and to grip a portion of the fabric, as in a clamp, which has a very pronounced effect in preventing the turning or rolling of the pin.

70 In the drawing, 1 designates the plate forming the body of the bar-pin, and 2 the flanges projected rearward along its edges, with a recess or space 3 between the flanges. The pivot 4 forms the joint for the pin-tongue 5, and the hook 6 at the end opposite the pivot engages the point of the tongue, which may be secured therein by a safety-catch 7 in the usual manner.

75 A seat 8 is formed as a bridge or block 100 between the side-flanges 2, intermediate to the hook and pivot. This seat does not project materially above the flanges.

80 The pin-tongue 5 is curved convexly upon the side next the seat 8, as at 5 in Fig. 2; 105 and the pivot 4 is located near the level of the flange-tops, as shown in Fig. 2, so that when the tongue is closed it presses upon the seat and lies parallel with the flange-tops.

85 The curvature of the tongue is indicated 110 by contrast with a straight dotted line 5, extended from its pivot to its point in Fig. 3,

and is so proportioned as to press the tongue 5 strongly upon the seat 8, and thus firmly grip the fabric to which the bar-pin is applied.

5 The middle portion of the fabric grasped by the tongue is gripped upon the seat 8, but at each side of said seat the fabric is crowded into the flanged space, thus drawing the pin close to the fabric.

10 It is obvious that the bar-pin can freely roll on the tongue if the fabric is merely pierced by the tongue, but in the present construction the pin-tongue grips the fabric like a vise and holds it positively in the desired position.

The fabric when thus gripped is indicated at 10 in Fig. 4, pressed by the pin-tongue 5 upon the seat 8.

A supplemental seat is formed of a block 20 11 fitted between the side-flanges, as shown in Fig. 1, close to the bearing 4' which supports the pivot 4.

This bearing serves as a stop to set the pin-tongue parallel with the tops of the flanges 2 when the pin-tongue is pressed upon the seat 8.

This stop is made of such height as to ar-

rest the pin-tongue slightly before it touches the seat, thus pressing the tongue upon the block and holding the tongue stiffly during 30 the use of the bar-pin.

Having thus set forth the nature of the invention what is claimed herein is:

1. A bar-pin having a body-plate, flanges upon the edges of the rear side forming a 35 recess between the flanges, an integral seat upon the rear side of the pin disposed transversely between the ends of the body, and a pin-tongue supported close to the recess 40 between the flanges, and operated to grip the dress fabric close to such recess and thus draw the pin close to the surface of the fabric.

2. A bar-pin having a body-plate with flanges upon its edges at the rear side, a seat 45 disposed transversely between the flanges near the middle of their length, and a pin-tongue pivoted upon the body substantially at a level with the flange tops and operating to hold the pin close to the fabric engaged. 50

In testimony whereof I have hereunto set my hand.

ACHILL BIPPART.
